ELECTRIC HEATING UNIT CONTROL

FIG. 1.

Diagram illustrating a power distribution and control system. The main power source is connected to terminals L_2 , N , and L_1 . The circuit branches into several paths:

- Left Path:** Terminals 86 and 38 are connected to a switch assembly. This assembly includes a coil 46 , a plunger 47 , a contact 44 , a spring 59 , and a lever 58 . The assembly is connected to terminal 72 .
- Central Path:** Terminals 83 and 93 are connected to a switch assembly. This assembly includes a coil 35 , a plunger 42 , a contact 30 , a spring 33 , and a lever $42a$. The assembly is connected to terminal 26 .
- Right Path:** Terminals 80 and 82 are connected to a switch assembly. This assembly includes a coil 28 , a plunger 27 , a contact 25 , and a lever 40 . The assembly is connected to terminal 10 .
- Bottom Path:** Terminals 85 , 84 , and 81 are connected to a switch assembly. This assembly includes a coil $12b$, a plunger $12a$, and a contact 12 . The assembly is connected to terminal 10 .
- Rightmost Path:** Terminals 16 and 15 are connected to a switch assembly. This assembly includes a coil 22 , a plunger 21 , a contact 41 , and a lever 20 . The assembly is connected to terminal 11 .
- Bottom Left:** Terminals 12 and 10 are connected to a switch assembly. This assembly includes a coil $12b$, a plunger $12a$, and a contact 12 .

Diagram illustrating a lighting fixture assembly. The fixture is shown in an exploded view, with various components labeled with numbers. On the left, a circular component is labeled 42. A bracket labeled 33 is attached to a vertical support. A horizontal arm labeled 72 extends from the support. A vertical support labeled 30 is shown with a bracket labeled 42a. A central vertical support labeled 26 is connected to a horizontal arm labeled 25. On the right, a vertical support labeled 20 is connected to a horizontal arm labeled 41. The word "Flash" is written near the rightmost assembly.

Technical drawing showing a heating element assembly. On the left, a circular component labeled '42a' is connected to a '33' terminal. A '72' terminal is also shown. A dashed line labeled '30' extends from this assembly. A '26' terminal is connected to a vertical tube labeled '25'. Another vertical tube labeled '20' is connected to a circular component labeled '41'. A dashed line labeled '30' extends from this assembly. The text 'Flash' and 'High Heat' is written above the components.

ELECTRIC HEATING UNIT CONTROL

Walter H. Vogelsberg, Glen Burnie, Md., assignor
to Proctor Electric Company, Philadelphia, Pa.,
a corporation of Pennsylvania

Application October 8, 1951, Serial No. 250,326

9 Claims. (Cl. 219—20)

1

The present invention relates to wattage controllers for use with electric range surface heating units and more particularly to a controller for use in effecting initial rapid heating of the surface unit to bring said unit to its operating temperature quickly.

Electric ranges currently being manufactured are equipped with four surface heating units. These usually comprise two heating units approximately 6" in diameter and of approximately 1200 watts capacity, a deep well cooker having a heating unit of approximately 1200 watts capacity, and an 8" heating unit having approximately 2100 watts capacity. This latter unit gives the housewife a large amount of available heat for use with the larger cooking pots or oversize pans, pressure cookers, etc. The present invention relates to an improved controller and electrical system that is particularly useful with this large surface heating unit.

To effect rapid heating of the surface heating units by first using a high wattage or over-energizing and subsequently reducing that wattage to some lower normal value, has been generally known as "flashing." In flashing, the 1200 watt 6" units are operated at 4800 watts for approximately 30 seconds, and then the wattage is reduced to 1200 watts after the unit has reached the desired operating temperature. This 4-to-1 energization ratio between flash and normal operation can be obtained by a series parallel arrangement of two approximately equal resistance coils. It is also possible to obtain this in the smaller units by switching from a 236 volt to a 118 volt line. A similar two-coil series-parallel approach on the larger 8" units would give approximately 3400 watts during the flash interval. This wattage is considered excessive and is, therefore, avoided in the design of present day electric ranges. One approach to flashing the larger 8" units without overloading the supply lines to an electric range is shown in the Patent No. 2,419,083, issued April 15, 1947, to J. W. Myers. The patent arrangement, however, requires a three-coil heating unit and only a portion of the unit flashes to its full operating temperature while the remainder is not energized until the flash interval is completed.

A prime object of this invention is to provide a system for flashing an electric range surface unit such that the heating unit will heat initially and simultaneously over its entire surface in attaining its operating temperature, and thereafter will operate at this temperature throughout the entire surface of the heating unit.

2

A further object is to provide a system and controller therefor that will not overload the supply line to an electric range and will show economies over previous arrangements.

5 In my copending application Serial No. 157,933, filed April 25, 1950, a flasher switch construction system is provided for use with a 6" heating unit. That device employs a single thermostatic control member both to time the flash operation and to control the normal operation. Further, it makes use of a direct connection of a heating unit across the line to obtain "high" or 100% input in order to insure continuous energization of the heating unit. Moreover, the system employs a thermostat which has a memory or history characteristic which operates to prevent damage to the system on repeated attempts at refloating by the user.

20 Another object of this invention is to provide an 8" flasher system and switch construction which utilizes these features, and which is easily adapted to fit the general framework of the 6" flasher switch mentioned above.

Briefly, the present invention contemplates the provision of an 8" surface unit comprising two coils, one having twice the resistance of the other, in combination with a 3-wire electrical supply system such that during the flash period the smaller resistance coil is energized by a line voltage E , e. g. 118 volts, while the double resistance coil is energized by a line voltage $2E$ of twice the first voltage, e. g. 236 volts. During normal operation, the resistance coils are serially connected across the 236-volt line. By such an arrangement, a flash wattage in the vicinity of 4800 watts is supplied for approximately one minute, while during run the energization is approximately 2100 watts. This, of course, is the situation for a "high" heat condition. Lower heats are provided by reducing the time that the 4800 watts is supplied and during normal or "run" operation by cyclically making and breaking the 2100 watt circuit at a predetermined average rate.

Referring now to the accompanying drawings,
45 Fig. 1 is a diagrammatic illustration of the system in its "off" condition;

Figs. 2 to 5 show the conditioning of the various switch elements during the various operating conditions;

50 Fig. 6 is a rear view of the controller with its various connections;

Fig. 7 is an elevational section taken along line 7—7 of Fig. 6;

55 Fig. 8 is a fragmentary elevational section taken along line 8—8 of Fig. 6;

Fig. 9 is a face view of two of the switch members and their cooperating cam;

Figs. 10 to 13 are similar views taken along line 10—10 of Fig. 9, showing various positionings of the switch parts of Fig. 9 during different conditionings of the controller;

Fig. 14 is a front face view of the controller with the cover and cam removed; and

Fig. 15 is a sectional view along line 15—15 of Fig. 14 with the cover and cam in place.

The system for flashing, as shown diagrammatically in Fig. 1, includes a 3-wire supply designated at L₁, N, and L₂, and a control device generally designated as 10 under the control of the user through a manual adjusting knob 11 for controlling energization of an electric range surface unit 12 comprising heating elements or coils 12a and 12b. To obtain approximately 4800 watts energization (4725 watts, to be exact) during the flash and approximately 2100 watts energization during normal conditioning, heating element 12a is chosen at 8.84 ohms while heating element 12b is selected at 17.68 ohms. These resistances are chosen for a nominal line voltage (i. e. L₁ to L₂) of 236 volts with a nominal voltage from line to neutral (N) of 118 volts. The heating coils, if of the rod type, are of equal cross-sections and are designed to give the same wattage per lineal inch of coil during normal or run operation. Fig. 1 shows a load 15, under control of switch 16, which may be considered to be the oven heating unit or any other load in the same range and on the same range circuits. The control device 10, during the overenergization period of heating unit 12, deenergizes load 15 to avoid exceeding the overall rating of the range during that interval. This is termed "load dropping" and is well known in the art.

The control device 10 is generally similar to that shown in my above-mentioned application but differs therefrom in certain respects as hereinafter described. For the purpose of this application, it suffices to illustrate and describe the control device only to the extent necessary for a clear understanding of this invention. In Fig. 1, the dotted lines represent mechanical connections or engagement of parts in operation.

Control device 10 includes a manually operated "on-off" switch blade 20 and its cooperating relatively stationary contacts 21 and 22, two latch controlled blades 25 and 26 and their cooperating relatively stationary contacts 27, 28 29 and 30, a manually operated switch blade 33, a switch blade 35 which is either manually operated or latch controlled, and a continuously adjustable ambient compensated thermostat control switch 38. Manual control knob 11, operating through shaft 40, controls the following: the movement of cam 41, which can manipulate blade 20 from an "off" position where it engages contact 21 to an "on" position, where it engages contact 22; cam 42 which can manipulate blades 33 and 35; cam 43 which controls thermostatic switch 38 by forcing an adjustable blade 44 with its contact 45 into engagement with a thermostatic member 46 thru its contact 47 to thereby preselect the various input levels; and cam 48 to actuate a latch member 50 which is pivoted about axis 51 for actuating blades 25 and 26, respectively, through extension arms 52 and 53. Although the various cam members are shown as individual peripheral cams operated from the same shaft, it is preferred to incorporate the cam races into a single molded member having a plurality of face cam surfaces. This single cam is

shown in Figs. 7 and 15 as member 54. This cam is rotated through shaft 40 by means of control knob 11 or its equivalent. Control knob 11 is marked with suitable indicia (not shown), permitting the user to select a full range of inputs from some low or "simmer" heat to the "high" or 100% energization, i. e. 2100 watts.

The latch 50 is provided with latching surface 56 which is engageable by a U-shaped self-heating bimetallic prop member 57. Blades 25 and 26 are spring biased, preferably by their own resilience, toward the right as viewed in Fig. 1, and are held in engagement with contacts 28 and 30, respectively, by latch 50. In the "off" position the lobe of cam 43 holds the latch 50 in this conditioning, while at other positions of the control knob 11 prop 57 is used to hold blades 25 and 26 in engagement with contacts 28 and 30 during the flash interval.

The thermomotive member 48 comprises bimetal 58 and heater 59 insulated from one another. On heating, the thermomotive member moves generally toward the left causing separation of contacts 47 and 45. With the heater 59 deenergized, the thermomotive member 48 cools and flexes generally back toward the right, with an eventual reestablishment of the circuit by engagement of contact 47 with 45. This thermostatic device is generally of the type disclosed and claimed in my co-pending application Serial No. 157,932, filed April 25, 1950, now Patent 2,623,137. The usefulness of this device in a flasher is set forth in that application.

The switch members described thus far are generally similar to those shown in my first-mentioned application No. 157,933. The construction of blades 33 and 35 does differ and this can best be explained by reference to Figs. 9 and 10. Switch blade 33 is in the form of a bent strip fixed to the switch casing at 60 and has a reverse bend at 61 and an extending portion 62 which carries an electrical contact 63. The blade is self-biased toward the cam 42 and is provided with a raised portion 64 for actuation by the lobe of said cam. The self-biasing movement of said blade is determined by engagement of raised portion 64 with the flat of said cam. The switch case is recessed at 65 to accommodate the extension 62, and a hole 66 provided in said switch case accommodates a finger extension 67 of said blade for angularly positioning the switch blade with respect to the axis of the cam.

Switch blade 35 is in the form of a strip riveted to the switch case at 68 and is self-biased toward cam 42 which it is adapted to engage through an extension 69. An insulating button 70, held by fingers 71 onto said blade, is adapted to engage the latch controlled blade 26. Blade 35 can, therefore, receive motion from either the latch controlled blade 26 or the lobe on cam 42.

Blade 35 affixed to the switch case at 68 connects through a special bus 72 (Figs. 6 and 7) to the base of bimetal 59 of the thermostat. This bus runs along the back of the switch case, making a 90 degree bend out of this plane at 72a and then is bent to lay under the bimetal (Fig. 8). The rivet connection at 68 is insulated from surrounding members at the switch case rear by an insulating barrier 73. An insulating barrier is also molded into the switch case at 74 to isolate the rivet connection from stationary contact 30 and blade 26.

Referring now to the mode of operation of the present invention, in the "off" position (Fig. 1) of the switch, heating unit 12 is disconnected

from lines L_1 and L_2 of the power supply. One end of heating element $12a$, however, is connected through blade 26 and contact 39 to the neutral connection, preferably grounded, of the power supply. Continuity of electrical supply is maintained to the heating load 15 through line L_1 , blade 20 , contact 21 and switch 49 .

Assume first that the control knob 11 is rotated to one of the operating heats less than "high" (Fig. 2). Cam 41 forces blade 20 into engagement with contact 22 , and cam 42 is moved out of the way of blade 39 permitting it to engage blade 35 . The lobe of cam 48 is also moved out of the way of the latch member 59 , permitting the prop member 57 to hold the blades 25 , 26 and 35 into their overenergization position, while cam 43 forces blade 45 into engagement with thermomotive member 46 and pre-stresses it in an amount depending upon the desired heat. Under this conditioning, the heating unit 12 is overenergized, for coil $12a$ is placed across the 118 volt line, i. e., lines L_1 and N , while coil $12b$ is placed across the 236 volt line, i. e., lines L_1 and L_2 . The circuit may be traced as follows: Starting from L_1 current flowing to the heating unit proceeds through blade 20 , contact 22 , blade 25 , contact 23 , to the junction of coils $12a$ and $12b$. One portion of current then travels through coil $12a$ to blade 26 , contact 39 , and thence to line N . Another portion of the current flows through coil $12b$, thermostat contacts 45 and 47 , heater 59 and thence to line L_2 . Engagement of blades 35 and 33 places the bimetallic prop 57 in shunt across contacts 45 and 47 of thermostatic switch 38 . However, the low resistance path provided by these contacts does not permit sufficient current to flow through the shunt path of the prop 57 for actuation of the latter. The overenergization or flash period of heating unit 12 is determined by the thermostatic switch 38 and can be varied according to the setting of said thermostat through cam 43 and knob 11 . The length of the overenergization period is thus synchronized with the particular selected heat of the heating unit so that the heating unit heats rapidly to a preselected temperature. The length of the overenergization period is also determined by the residual heat in thermomotive member 46 so that the heating unit will not be dangerously overenergized. This is known as the "history heater effect." Sufficient mass is usually associated with the thermomotive members to give it a time constant commensurate with that of the heating unit used. During the flash interval the circuit to load 15 is deenergized for none of contacts 29 , 27 , or 21 are energized at L_1 potential.

Upon attainment of a predetermined conditioning of thermostatic switch 38 , contacts 45 and 47 of said switch separate, causing the current, which had been flowing from heating element $12b$ through said contacts to line L_2 , to travel through prop latch 57 , blades 33 , 35 , bimetal 58 , heater 59 , and thence to line L_2 . The effect of this is to cause flexing of the upper end of bimetal prop 57 toward the left to thereby release latch 59 under the bias of blades 28 , 26 and 35 , causing blade 25 to engage contact 27 , blade 26 to engage contact 29 and blade 35 to bear against surface $42b$ of cam 42 . The control device 10 is now in its normal "run" condition (Fig. 3) for the selected heat less than "high." Under this conditioning, heating elements $12a$ and $12b$ are serially connected across the 236 volt line, i. e. L_1 and L_2 , and the selected heat is maintained by cyclically

opening and closing of contacts 45 and 47 of thermostatic switch 38 .

The circuit for the "normal" energization for heats less than "high" may be traced from L_1 , to blade 20 , contact 22 , blade 25 , contact 27 to contact 29 , blade 25 , coil $12a$ through coil $12b$ to adjustable blade 44 of thermostatic switch 38 , contacts 45 and 47 , heater 59 , and then to line L_2 . During this "normal" energization of the heating unit, the electrical supply is restored to the load 15 through L_1 , blade 20 , contact 22 , blade 25 , contact 27 and switch 46 . Under continuous energization of the serially connected coils $12a$ and $12b$ across the 236 volt line, a total of 2100 watts will be consumed. At heats less than full, the serially connected heating coils are cyclically energized and deenergized by thermostat 38 to give varying percentages of the 2100 watt load, depending upon the thermostat setting.

Full 100% energization of the heating unit 12 , i. e. "high" heat, is obtained by connecting heating unit sections $12a$ and $12b$ serially across L_1 and L_2 independently of the thermostat switch contacts. The circuit for this connection may be traced from line L_2 through heater 59 , bimetal 58 , closed contact blades 33 and 35 (Fig. 5), prop latch 57 , heating elements $12b$ and $12a$ in series, and thence through blade 26 , contact 29 , contact 27 , blade 25 , contact 22 , blade 20 , to line L_1 . In the "high" heat position of control knob 11 , lobe $42a$ holds blade 35 in engagement with blade 33 , as shown in Figs. 4 and 5. The overenergization conditioning of the heating unit at "high" heat is similar to that during overenergization at heats less than full, except that the lobe $42a$ of cam 42 is used to effect engagement of blades 35 and 33 . This is in addition to the action of blade 26 which forces blade 35 into engagement with blade 33 through projection 70 , when blade 26 is latch-held in engagement with contact 39 . Thus, regardless of whether blades 25 and 26 are latch-held in contact with contacts 28 and 39 or are in a released position wherein they engage contacts 27 and 29 , blade 35 engages blade 33 . The overenergization period is terminated upon opening of contacts 45 and 47 of thermostatic switch 38 , permitting the overenergization current to flow through prop latch 57 , blades 33 , 35 and bimetal 58 . The flexing of prop 57 releases latch 59 , permitting blades 25 and 26 to engage contacts 27 and 29 respectively, to institute serial connection of coils $12a$ and $12b$. During the series connection in the high heat position, contacts 45 and 47 of thermostatic switch 38 are normally maintained separated for heater 59 is continuously energized. The advantages of the shunting of the thermostatic contacts at the high heat positions in flasher systems has been brought out in my first-mentioned copending application No. 157,933.

From the foregoing description it will be seen that the control device 10 shown diagrammatically in Fig. 1 has been embodied (Figs. 6 to 15) in a switch structure similar to that disclosed in my aforementioned application No. 157,933. It will be noted that the particular system shown in Fig. 1 requires that minimum changes be made in the switch structure of that application for adaptation therein.

Fig. 6 shows the manner in which the switch connects the heating unit 12 to the electrical supply lines. The terminal connections can best be understood by a comparison of Fig. 6 and Fig. 1. A terminal 34 which is connected to the base of blade 20 is used for a connection to line

L₁. A terminal 31 attached to stationary contact 28 connects to the junction of coils 12a and 12b. A terminal 32, which is connected to bus 93 carrying contacts 21, 27 and 29, connects to the load 15. A terminal 33 connects stationary contact 30 to the neutral side of the line. A terminal 34 attached to blade 26 connects to one side of coil 12a. A terminal 35 attached to the base of prop latch 57 connects to one side of heating unit 12b, while a terminal 36 secured electrically and mechanically to the base of heater 59 of thermostat 38 connects to L₂.

It should be pointed out that the release bimetal 57 is placed under conditions different from those of the prop latches of the earlier, smaller heating unit flashers. At the termination of overenergization, release bimetal 57 receives 13.4 amperes, while during "run" at the "high" heat position where it is continually energized, it receives 8.9 amps. With the 6"-2-coil flasher of the aforementioned application No. 157,933, the current of termination of overenergization is 21.2 amps., while the current during "high" heat on "run" is only 5.3 amps. The material used for the release bimetal in the present device is known to the trade as "High-Heat 47," and is .025" thick. The inactive section of the bimetal that is directly under the latch is of substantial length to improve the efficiency and the dissipation characteristics of the latch prop. Further the initial bias on the release bimetal when cold is $\frac{3}{2}$ ". The thermostat 38 is essentially the same as that of the aforementioned application except that a new material is selected for heater 59. This resistance is chosen so as to keep the watts dissipated by the thermomotive member substantially the same as the device of the previous disclosure.

In switching from the overenergization condition of the heating unit to the normal "run" condition, as described above, the latch 58, on release, permits blades 25 and 26 to move from contacts 28 and 30 to contacts 21 and 29, respectively. During this switching, blade 25 is maintained at L₁ potential while stationary contact 30 is maintained at neutral potential. To avoid the possibility of drawing an arc through the medium of moving blade 26 between stationary contact 30 and contact 29 which assumes an L₁ potential as blade 25 engages contact 27, latch 58 is damped. The damping of latch 58 slows down the movement of blades 26 and 25 to such an extent that any arc established between contact 30 and blade 26 will be extinguished before the arc-over can occur. The damped latch construction is disclosed and claimed in an application to John J. Lawser, Serial No. 254,037, filed October 31, 1951. Briefly, latch 58 (Figs. 7 and 9) is provided with a hole 88 into which is inserted an absorbent, resilient pad 90 such as sponge rubber or felt. The latch rides between lands 91 and 92 on the switch case. The space between these lands is approximately $\frac{5}{8}$ " and pad 90 before insertion between the lands is approximately $\frac{3}{8}$ ". Before insertion the pad is impregnated with a special fluid to cooperate therewith and to provide damping action. It has been determined that a fluid such as Dow-Corning DC 200 having a viscosity of 60,000 cstks. provides an effective and satisfactory damping action.

While the present invention is particularly intended for use in the manner described, it is intended that the invention shall be applicable to

any use to which it may be applied by those skilled in the art.

I claim:

1. A device for effecting different modes of energization of an electrical heating unit having a first element of predetermined resistance and a second element of substantially twice the resistance of the first element, from a three-wire supply line having two main conductors and a neutral conductor supplying one voltage between a main conductor and the neutral conductor and a second voltage between the main conductors substantially twice the value of the first voltage, said device comprising: three load terminals, one for connection to an end of each of said elements and the other two for connection respectively to the other ends of said elements; three input terminals, one for connection to said neutral conductor and the other two for connection respectively to said main conductors; two-position switch means; circuit means controlled by said switch means in one position thereof for connecting said first element between a main conductor and the neutral conductor and for simultaneously connecting said second element between the two main conductors, circuit means controlled by said switch means in the other position thereof for connecting both of said elements in series between said main conductors; means for initially establishing the first position of said switch means, thereby to effect relatively high wattage input to the two-element heating unit and rapid heating of the same to a desired temperature; and means for establishing the second position of said switch means upon attainment by said heating unit of said temperature, thereby to reduce the wattage input to the heating unit for normal operation of the same.

2. A device according to claim 1, further characterized in that said switch means is biased toward its second position, and further including latch means for initially retaining said switch means in its first position, and means for effecting release of said latch means upon attainment by the heating unit of the desired temperature.

3. A device according to claim 2, wherein said latch means includes a current-operable thermomotive release element included in said circuit connections, and said release effecting means comprises current-operable thermostatic switch means also included in said circuit connections and having contacts in shunt relation with said release element.

4. A device according to claim 3, wherein said thermostatic switch means is adjustable for selection of different temperatures of said heating unit, and said thermostatic switch means serves to control the normal operation of the heating unit for selected temperatures less than the highest selectable temperature, the device further including means for effecting continuous energization of the heating unit during operation at the highest selectable temperature.

5. A device according to claim 1, including means for preventing energization of loads subsequent to said heating unit on the same supply line during the supply of high wattage to said heating unit.

6. In a system for effecting overenergization of an electrical heating unit, and for effecting subsequent normal energization of the heating unit, from a three-wire supply line having two main conductors and a neutral conductor supplying one voltage between a main conductor and the neutral conductor and a second voltage between the

main conductors substantially twice the value of the first voltage, a heating unit comprising a first heating element having a predetermined resistance and a second heating element having a resistance substantially twice that of the first element, two position switch means, circuit means controlled by said switch means in one position thereof for connecting said first element between a main conductor and the neutral conductor and for simultaneously connecting said second element between the main conductors, circuit means controlled by said switch means in the other position thereof for connecting both of said elements in series between said main conductors, means controlled according to the temperature condition of said heating unit for effecting actuation of said switch means from said first position to said second position upon attainment of a desired operating temperature of the heating unit, a switch for interrupting supply of current to loads subsequent to said heating unit on the same supply line during the first-mentioned connections of said elements, and a common bus carrying contacts of said switch means and said switch serving to effect circuit continuity to subsequent loads during the last-mentioned connections of said elements and during the "off" condition of the system.

7. In a system for effecting overenergization of an electrical heating unit, and for effecting subsequent normal energization of the heating unit, from a three-wire supply line having two main conductors and a neutral conductor supplying one voltage between a main conductor and the neutral conductor and a second voltage between the main conductors substantially twice the value of the first voltage, a heating unit comprising a first heating element having a predetermined resistance and a second heating element having a resistance substantially twice that of the first element, two position switch means, circuit means controlled by said switch means in one position thereof for connecting said first element between a main conductor and the neutral conductor and

- for simultaneously connecting said second element between the main conductors, circuit means controlled by said switch means in the other position thereof for connecting both of said elements in series between said main conductors, said switch means being biased toward said second position, latch means for initially retaining said switch means in said first position, and means for effecting release of said latch means upon attainment of a desired temperature of the heating unit, whereby to effect movement of said switch means from said first position to said second position.
8. In a system according to claim 7, wherein said latch means includes a current-operable thermomotive release element, and said release effecting means comprises current-operable thermostatic switch means having contacts in shunt relation with said release element.
9. In a system according to claim 8, wherein said thermostatic switch means is adjustable for selection of different temperatures of said heating unit, and said thermostatic switch means serves to control the normal operation of the heating unit for selected temperatures less than the highest selectable temperature, the system further including means for effecting continuous energization of the heating unit during operation at the highest selectable temperature.
